US00D698792S

(12) **United States Design Patent**
Lin et al.

(10) **Patent No.:** **US D698,792 S**
(45) **Date of Patent:** **** Feb. 4, 2014**

(54) **MEMORY MODULE**

(75) Inventors: **Yi-Ting Lin**, Hsinchu (TW); **Hsi-Ming Tsai**, Hsinchu (TW); **Peter Leekuo Chou**, Fountain Valley, CA (US)

(73) Assignee: **Kingston Digital, Inc.**, Fountain Valley, CA (US)

(**) Term: **14 Years**

(21) Appl. No.: **29/410,195**

(22) Filed: **Jan. 5, 2012**

(51) LOC (10) Cl. **14-02**

(52) U.S. Cl.

USPC **D14/435**

(58) **Field of Classification Search**

USPC D14/435, 356, 242, 436, 433, 474, 240, D14/496, 385, 358, 480.1-480.7; 360/97.01, 685, 686, 752, 737, 732, 360/784, 803; 439/135, 144, 139-141, 147, 439/136, 638, 518, 131; 365/51, 63, 131; 710/52, 300, 313; 711/115, 103, 154, 711/161-162; 70/58; 323/210; 713/186, 1; 382/124; 235/492; D13/147

CLAIM

The ornamental design for a memory module, as shown and described.

DESCRIPTION

FIG. 1 is a perspective view of a memory module showing the claimed design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

1 Claim, 4 Drawing Sheets
